UNITED STATES PATENT OFFICE.

LOUIS N. D. WILLIAMS, OF OGONTZ, PENNSYLVANIA.

TAKE-UP MECHANISM FOR KNITTING-MACHINES.

1,133,078.

Specification of Letters Patent. Patented Mar. 23, 1915.

Application filed December 18, 1911, Serial No. 836,584. Renewed August 15, 1914. Serial No. 856,987.

To all whom it may concern:

Be it known that I, LOUIS N. D. WILLIAMS, a citizen of the United States, residing in Ogontz, Montgomery county, Pennsylvania, have invented certain Improvements in Take-Up Mechanism for Knitting Machines, of which the following is a specification.

The object of my invention is to so construct the web take-up mechanism for a knitting machine having a rotating needle cylinder that it will be as reliable and effective in operation as the web take-up mechanism employed in connection with a knitting machine having a non-rotating needle cylinder.

This object I attain in the manner herein-after set forth, reference being had to the accompanying drawings, in which—

Figure 1 is a view, partly in vertical section and partly in elevation, of sufficient of a knitting machine to illustrate the application thereto of web take-up mechanism constructed in accordance with my invention; Fig. 2 is a view, partly in plan and partly in horizontal section, on the line *a—a*, Fig. 1; Fig. 3 is a transverse section on the line *b—b*, Fig. 1; Figs. 4, 5, and 6 are views, similar to Fig. 1, of parts of the take-up mechanism, illustrating certain modifications of my invention; Fig. 7 is a transverse section on the line *c—c*, Fig. 4; Fig. 8 is a transverse section on the line *d—d*, Fig. 5, and Fig. 9 is a plan view of parts of Fig. 6, on the line *e—e*, but on a smaller scale.

Referring in the first instance to Figs. 1, 2 and 3 of the drawings, 1 represents the supporting framework of the machine mounted upon legs 2 and carrying a table 3 in which is mounted, so as to be free to rotate, a needle cylinder 4, the latter, in the present instance, being carried by a ring 5 with bevel teeth 6 engaged by a bevel wheel 7 on the driving shaft 8 of the machine. At the bottom of the frame 1 is an annular platform 9 in which is mounted, so as to be free to rotate, a ring 10, the latter being caused to rotate with the needle cylinder by reason of standards 11 which connect the rings 5 and 10.

Depending from the ring 10 are bars 12 which carry at the bottom a cross head 13, this cross head, and the ring 10, providing bearings for a pair of rods 14 which are free to slide vertically in said bearings and carry at their upper ends bearings for a pair of take-up rolls 15, which may be similar to

those commonly employed in stationary-needle-cylinder knitting machines and may be geared together and to a worm 16 so as to be positively rotated as is common in 60 such stationary-needle-cylinder machines.

The worm 16 is carried by a vertical shaft 17 which passes through an opening in the ring 10 and is adapted at its upper end to a bearing in a bracket 18 projecting from one 65 of the take-up roll bearings and at its lower end to a bearing 19 on a cross head 20, which connects the lower ends of the bars 14 and has a central hub 21 to which is secured, in any suitable manner, the upper end of a 70 vertical shaft 22 which extends below the cross head 20 and has mounted upon it, so as to be freely rotatable independently of it, the chain wheel 23, which is connected by an endless chain 24 to a chain wheel 25 at the 75 lower end of the vertical shaft 17.

A belt and pulleys may, of course, be substituted for the chain and chain wheels if desired, or any other available form of gearing may be employed for connecting the 80 shafts 17 and 22. Pivotaly mounted upon the under side of the chain wheel 23 are a pair of pawls 26 which engage with ratchet teeth 27 formed on the upper end of the tubular hub 28 of a bevel wheel 29, said 85 tubular hub being mounted so as to be free to turn in a bearing 30 at the inner end of an arm 31, the latter being rigidly mounted upon one of the legs 2 of the machine and projecting inwardly therefrom. The bevel 90 wheel 29 is in mesh with a bevel wheel 32 carried by a horizontal shaft 33 which is free to turn in a bearing 34 on a bent arm 35 projecting laterally from the arm 31, as shown in Fig. 3, said shaft 33 also carrying 95 a belt pulley 36 which is driven by a belt 37 from a belt pulley 38 on a shaft 39, which is provided with another pulley 40 for the reception of a belt 41 from a pulley 42 on the driving shaft 8 of the machine, as shown in 100 Fig. 1. The shaft 39 is carried by and is free to rotate in a bearing 43 on a lever 44, which is pivotally mounted upon a depending portion 45 of the arm 31 and terminates at its inner or free end in a ring or yoke 105 46 provided with inwardly projecting pins 47 which engage a grooved collar 48 secured to the lower end of the shaft 22, as shown in Fig. 1.

The knitted web passes downwardly from 110 the needle cylinder 4 and between the take-up rolls 15 and may then be permitted to ac-

cumulate below the same, the bars 12 and cross head 13, if desired, serving for the support of a cage or basket for the reception of the web after it leaves the take-up rolls. The take-up roll bearings, the depending rods 14 and the cross head 20 constitute a take-up roll frame which, owing to the ring 10 is caused to rotate in unison with the needle cylinder but is free to rise and fall in respect thereto, said rising and falling movements being, through the medium of the shaft 22, grooved collar 49 and pins 47, transmitted to the free end of the pivoted lever 44 and by said lever to the pulley 40 carried thereby. As the knitted web is delivered from the needles of the cylinder 4 the take-up roll frame descends with said web and the pulley 40 is lowered until it tightens the belt 41 sufficiently to cause it to transmit power from the driving pulley 42 to the pulley 40. This power is transmitted through the medium of the shaft 39, pulley 38, belt 37, pulley 36, shaft 33 and bevel wheel 32 to the bevel wheel 29, and consequently to the ratchet teeth 27 on the upper end of the hub 28 of said bevel wheel. These ratchet teeth, by engagement with the pawls 26, impart rotative movement to the chain wheel 23 and thence through the chain belt 24 to the chain wheel 25, shaft 17 and worm 16, thereby imparting rotative movement to the take-up rolls 15, which climb upon the knitted web and consequently raise the take-up roll frame and lever 44, this movement continuing until the belt 41 has been slackened to such an extent that it fails to transmit driving power from the pulley 42 to the pulley 40, whereupon the further rotative movement of the take-up rolls is arrested until the further production of web has again permitted the take-up roll frame and lever 44 to descend sufficiently to again tighten the belt 41. During those periods when the belt 41 is slack and no rotative movement is being imparted to the bevel wheel 29 the chain wheel 23 rotates with the take-up roll frame and its shaft 22 and consequently imparts no rotative movement to the worm 16, the pawls 26, during this time, slipping over the ratchet teeth 27 on the hub of the bevel wheel 29, but the latter, when driven from the pulley 42 through the medium of the intervening devices described, rotates much faster than the take-up roll frame, and this excess movement is, through the medium of the ratchet teeth 27 and pawls 26, imparted to the chain wheel 23 and thence to the worm shaft 17 and worm 16, with the effect of turning the take-up rolls and causing them to rise upon the knitted web.

In the modified form of take-up mechanism shown in Figs. 4 and 7 I have substituted other power transmitting devices for the ratchet and pawl mechanism shown in

Fig. 1. In this modification the shaft 39 carried by the lever 44 is provided, in addition to the belt pulley 40, with a bevel wheel 50 which meshes with a bevel wheel 51 having a hub adapted to turn on a stud 52 on 70 the lever 44 and carrying at its upper end a chain wheel 53 which, by means of a chain 54, drives the lower member of a duplex chain wheel 55 mounted upon a tubular bearing 56 which surrounds the shaft 22, 75 and is carried by a foot 57 fixedly mounted upon the floor or other suitable support, the upper member of the duplex chain wheel 55 receiving the chain 24 which drives the chain wheel 25 at the lower end of the worm 80 shaft 17. The lever 44 may be pivotally mounted upon a bracket on one of the legs of the machine or upon any other available support.

In the modified construction shown in Figs. 5 and 8 the shaft 39 has a bevel wheel 60 which meshes with a bevel wheel 61 on an upright shaft 62 mounted in a bearing carried by a lever 63 which is pivotally mounted upon a bearing on the lever 44, co-axial with the shaft 39, as shown in Fig. 8, the lower arm of said lever 63 bearing upon a cam surface 64 on an arm 65 which may be rigidly secured to a leg of the machine or to the floor, or to both. As shown, it is secured to the floor and carries at its upper end the pin upon which the lever 44 is pivoted. At its upper end the shaft 62 carries a belt pulley 66, which, by means of a belt 67, drives a pulley 68 mounted upon a collar 69 on the shaft 22, so as to be free to turn on said shaft, the hub of said pulley 68 having formed on or secured thereto a spur wheel 70 which meshes with a similar spur wheel 71 at the lower end of the worm 105 shaft 17. In a construction of this type the belt 41 may be replaced by a chain belt 41^a and the belt pulleys 40 and 42 by chain wheel or pulleys, as shown for instance at 40^a in Fig. 5, in which case the latter may 110 rotate continuously, the rising and falling movement of the lever 44 not affecting the continuous driving connection between the chain belt and wheel or pulley. The operation of the take-up pulleys in this case is 115 dependent upon the slackening and tightening of the belt 67 which connects the pulleys 66 and 68, the action of the cam 64 upon the lever 63, as the lever 44 swings downwardly, causing said lever 63 to swing the 120 pulley 66 outwardly so as to tighten the belt 67 sufficiently to impart movement to the pulley 68 and thence to the worm shaft 17, and the rise of the lever 44 serving to relieve the lever 63 from the pressure of the cam 125 64 to an extent sufficient to permit the inward swinging movement of the pulley 66 and the slackening of the belt 67 to the non-transmission point. In order to properly resist the lateral strain upon the shaft 22, 130

the latter is, at a point below the pulley 68, adapted to a bearing 65^a on an arm 65^b projecting from the same base as the arm 65, or otherwise mounted.

5 It will be noted that in all of the constructions thus far described the conditions as to primary power transmission are the same as in those knitting machines in which the needle cylinder is stationary, that is to say, the power is transmitted by means of a belt from a pulley on the main driving shaft of the machine to a pulley on a shaft carried by a lever which is pivotally mounted upon some fixed part of the framework 10 of the machine, neither of these members of the power transmitting mechanism rotating about the axis of the needle cylinder, and another respect in which the take-up mechanism resembles that of a stationary 15 cylinder machine is that the pulley which receives the driving belt 41 is located relatively close to the fulcrum of the lever which carries said pulley while the weight of the take-up roll frame is exerted upon 20 said lever at a point much farther from the fulcrum of the same, so that even if the weight of the take-up roll frame is partially counter-balanced, as it sometimes is in knitting webs of light and delicate texture, it 25 will still depress the belt pulley with sufficient force to insure good driving connection between the same and the depending driving belt and will thus insure the operation of the take-up rolls at the proper 30 times. Some of the features of my invention may, however, be embodied in take-up mechanism in which the swinging lever is not mounted upon the fixed framework of the machine but upon a support which rotates 35 with the needle cylinder, and in Figs. 6 and 9 I have shown one instance of a modification of this character. In this case a horizontally disposed pulley 40^b is mounted so as to rotate in the ring 9^a, the driving 40 belt 41^b being bent at right angles over idlers 73 so as to engage the grooved rim or periphery of the horizontal pulley 40^b. The lever 44^a is pivotally mounted upon a pin 74 carried by an arm 75 projecting from 45 one of the standards 11 which connect the needle cylinder drive ring and the ring 10, the latter being free to turn in the ring 9^a as before. The take-up rolls 15 and the worm shaft 17 are adapted to bearings 50 formed directly upon the lever 43^a, the latter also carrying the gears whereby power is transmitted from the worm 16 to the take-up rolls. The worm shaft 17 carries at its lower end a friction wheel or pulley 77, and, 55 as the lever 44^a descends, the rim or periphery of this friction wheel or pulley is pressed into driving contact with the inner face of the rotating pulley 40^b and is consequently rotated thereby so as to impart 60 to the take-up rolls 15, 65

the rise of the latter on the knitted web lifting the lever 44^a sufficiently to withdraw the rim of the wheel or pulley 77 from contact with the inner face of the pulley 40^b and thus stop the rotation of said friction wheel or pulley 77 and of the take-up rolls. 70

In all of the constructions illustrated the axes of both the driving pulley 42 and of the wheel or pulley driven thereby are fixed, in the sense that their axes do not rotate about the axis of the needle cylinder, and the belt which connects these pulleys is also freed from the necessity of traveling about the axis of the needle cylinder, consequently preserving the conditions under which these 75 elements of the take-up mechanism of a stationary cylinder machine operate, and therefore insuring reliability and effectiveness of such operation. Additional tension may be imparted to the knitted web, if desired, by 80 hanging extra weight upon the outer end of the lever 44, or the tension upon the knitted web may be lessened by means of weight applied to a counterbalance arm on said lever, 85 as in the usual practice. 90

I claim:

1. The combination, in take-up mechanism for a knitting machine having a rotating cylinder, of take-up rolls rotating with the needle cylinder and also susceptible of rising and falling movement in the plane of the knitted web, and take-up roll operating mechanism comprising a driving pulley which has no movement of rotation about the axis of the needle cylinder, a driven 95 pulley, a belt connecting said driving and driven pulleys, and means whereby on the fall of the take-up rolls movement is transmitted thereto from the driven pulley and on the rise of said rolls such transmission is 100 arrested. 105

2. The combination, in take-up mechanism for a knitting machine having a rotating needle cylinder, of take-up rolls rotating with the needle cylinder and also susceptible 110 of rising and falling movement in the plane of the knitted web, and take-up roll operating mechanism comprising driving and driven pulleys neither of which has movement of rotation about the axis of the needle cylinder, a belt connecting said pulleys, and means whereby on the fall of the take-up rolls movement is transmitted thereto from the driven pulley and on the rise of said 115 rolls such transmission is arrested. 120

3. The combination, in take-up mechanism for a knitting machine having a rotating needle cylinder, of take-up rolls rotating with the needle cylinder and also susceptible 125 of rising and falling movement in the plane of the knitted web, and take-up roll operating mechanism comprising a driving pulley which has no movement of rotation about the axis of the needle cylinder, a driven pulley which partakes of the rising and falling 130

movements of the take-up rolls, a belt connecting said driving and driven pulleys, and means whereby on the descent of the driven pulley movement is transmitted therefrom 5 to the take-up rolls and on the rise of said driven pulley such transmission is arrested. 4. The combination, in take-up mechanism for a knitting machine having a rotating needle cylinder, of take-up rolls rotating 10 with the needle cylinder and also susceptible of rising and falling movement in the plane of the knitted web, and take-up roll operating mechanism comprising a driving pulley which has no movement of rotation about 15 the axis of the needle cylinder, a driven pulley which also has no movement of rotation about the axis of the needle cylinder but partakes of the rising and falling movements of the take-up rolls, and means whereby on 20 the descent of said driven pulley motion is transmitted therefrom to the take-up rolls and on the rise of such driven pulley said transmission is arrested.

5. The combination, in take-up mechanism 25 for a knitting machine having a rotating needle cylinder, of take-up rolls rotating with said needle cylinder, and take-up roll operating mechanism having, as elements, belt connected pulleys, the driving pulley 30 rotating about an axis which is fixed in the sense that it has no movement of rotation about the axis of the needle cylinder, and the driven pulley being carried by a lever which is mounted upon a non-rotating portion of 35 the machine and is free to descend as the take-up rolls descend with the web or to rise as said take-up rolls climb the web.

6. The combination, in take-up mechanism 40 for a knitting machine having a rotating needle cylinder, of take-up rolls rotating with said needle cylinder, take-up roll operating mechanism having, as elements, belt connected pulleys, the driving pulley rotat-

ing about an axis which is fixed in the sense 45 that it has no movement of rotation about the axis of the needle cylinder, and the driven pulley being carried by a lever which is mounted upon a non-rotating portion of the machine and is free to descend as the take-up rolls descend with the web or to rise 50 as said take-up rolls climb the web, and means whereby said movements of the lever cause rotation or arrest of rotative movement of the take-up rolls.

7. The combination, in take-up mechanism 55 for a knitting machine having a rotating needle cylinder, of a take-up roll frame rotating with the needle cylinder but free to rise and fall in respect thereto, a lever in longitudinal but non-rotative engagement 60 with said take-up roll frame, and take-up roll driving mechanism having as elements a pair of pulleys, the driven pulley being carried by said lever and the driving pulley being mounted upon an axis which is fixed 65 in the sense that it has no rotative movement about the axis of the needle cylinder.

8. The combination, in take-up mechanism for a knitting machine having a rotating needle cylinder, of a take-up roll frame 70 rotating with the needle cylinder but free to rise and fall in respect thereto, said frame having a depending shaft with grooved collar thereon, a lever having pins engaging said grooved collar whereby it is in longitudinal but non-rotative engagement with 75 the shaft, and take-up roll operating mechanism carried in part by said lever.

In testimony whereof, I have signed my name to this specification in the presence of 30 two subscribing witnesses.
